UNITED STATES PATENT OFFICE.

WILLIAM S. SMITH, OF CAMBRIDGE, MASSACHUSETTS.

ELEVATOR-GATE LATCH.

1,358,592.

Specification of Letters Patent.

Patented Nov. 9, 1920.

Application filed August 25, 1919. Serial No. 319,638.

To all whom it may concern:

Be it known that I, WILLIAM S. SMITH, a citizen of the United States, residing at Cambridge, in the county of Middlesex and State of Massachusetts, have invented a new and useful Improvement in Elevator-Gate Latches, of which the following is a specification, reference being had therein to the accompanying drawings.

10 My invention relates to an automatic latch for elevator gates and is designed more particularly for locking manually raised gates used in connection with freight elevators.

15 The main object of my invention is the provision of means for automatically locking the gate after it has been raised and for automatically releasing the gate when the elevator leaves the floor landing.

20 A further object of the invention is the provision of means adapted for application to any form of construction of elevator gate at low cost of installation and which requires no cost of maintenance.

25 Another object of the invention is to provide means which is simple in construction and positive and efficient in operation.

Other objects of the invention will be more specifically set forth and described 30 hereinafter.

Briefly, my invention contemplates the provision of a latch normally inoperative but which, by the use of a cam or other suitable means on the elevator, is thrown into an operative position when the elevator comes to a stop at a floor landing and is held in that position so long as the elevator remains at the landing. The latch is so arranged that when the gate is pushed up 35 passing by it, the latch is thrown into a retracted position and as soon as the bottom of the gate has passed beyond the latch it is caused by the force of gravity to drop into a locking position, thereby holding the gate 40 so long as the elevator remains at the floor. When the elevator leaves the floor the cam leaves the latch allowing it to swing back into an inoperative position to release the gate automatically.

45 In the drawings illustrating the preferred embodiment of my invention,

Figure 1 is a front elevation of an elevator landing as viewed from the elevator, showing the elevator gate held in a raised position by a latch constructed and operated in accordance with my invention;

Fig. 2 is a cross-sectional view on line 2—2 in Fig. 1;

Fig. 3 is a front elevation of the latch on an enlarged scale, with the housing cut away 60 to show the latch in operative position with the gate locked;

Fig. 4 is a similar view of the latch to show the retracted position of the latch as the gate is being pushed upwardly by the 65 latch and before it reaches the position where it is to be locked;

Fig. 5 is a similar view showing the position of the latch when released by the cam on the elevator to permit the gate to drop 70 to close the doorway; and

Fig. 6 is a side elevation looking from left to right in Fig. 3.

Referring to the drawings 10 designates a housing open at the sides and having end 75 extensions 12, each provided with a hole 14 to receive a screw 16 whereby the housing may be secured to a fixed portion of the building adjacent the elevator gate when it is in a raised position. Within the housing is pivotally mounted on a screw-bolt 18 set in the upper part of the housing, a latch arm 20. This arm is loosely mounted on the bolt 18 to permit it to swing on its pivot, the upper end of the arm being provided 80 with two lugs 22 and 24 which are adapted to engage a stop 26 on the inside of the top of the casing and thereby to limit the swinging movement of the latch arm in both directions. Although it may be of any suitable shape in cross-section, the latch arm is preferably T-shaped in cross-section in 85 order to present a wide surface, that is the head of the T, to the rear or to the right as shown in the drawings, for a purpose to be 90 hereinafter explained. The lower end of the latch arm is curved forwardly and is bored to receive a pin 28 upon which is mounted a latch 30, the pivoted end of the latch being split so that that end of the latch 95 embraces the thin forward flange of the latch arm. The latch arm is pivotally movable on said pin 28 and on its lower side is provided with an enlargement 32 which is adapted to engage the end of the latch arm and thereby limit the outward movement 100 of the latch upon its pivot. The upper end of the latch is flat and cut at such an angle that it is substantially horizontal when the latch is in operative position, and serves as 105 the engaging surface for the elevator gate. The inner side of the latch is provided with a

longitudinal recess 34 in order to permit the latch to be thrown up closely against the latch arm, the thin forward flange of the latch arm lying in said recess.

- 5 Normally the latch swings in an inoperative position. The weight of the latch causes it to drop into a forward position with relation to the latch arm with the enlargement 32 in engagement with the lower 10 end of the latch arm 20 which causes the latch arm to swing on its pivot to a rearward position, that is, to the right referring to the drawings, and in this position the rear portion of the latch arm projects from 15 the housing. For throwing the latch arm forward and the latch into an operative position, a cam 36 is arranged on the elevator car at such point that when the car is at the floor landing the cam engages the back of 20 the latch arm and holds it in a forward position as shown in Figs. 3 and 4.

It will be observed that the pin 18 is arranged in the housing off-center and that a second hole 33 is bored in the housing at 25 the same elevation as the pin 18 but on the other side. This arrangement serves two purposes. It insures the rearward projection from the housing of the latch arm 20, when in an inoperative position, so that the 30 cam 36 may engage it and throw it forward and it enables the latch arm and latch to be reversed in the housing by mounting the pin in the hole 33 which permits the device to be secured on either side of the elevator 35 gate as desired.

In the use of my device the latch housing 12 is fastened to the door frame or wall 40 of the building adjacent to the elevator gate 42, and at such elevation that when the gate 40 is in a raised position the latch 30 is at a level just below the bottom of the gate as shown in Fig. 1. Where it is inadvisable to mount the housing in such a position that the latch engages the gate directly, an angle 45 iron 44 may be fastened to the gate by screws 46, said angle iron having its free end projecting in order to be held by the latch when the gate is locked. In Fig. 1, 48 designates the floor or landing, and in Fig. 2, 50 designates 50 the elevator car. The cam 36 is arranged on the elevator car at such elevation that when the car is at a landing, the cam engages the latch arm and holds it in a forward operative position, the cam having 55 curved end portions so that the latch arm will ride up on the cam when the latter makes or breaks engagement with it. By regulating the length of the cam 36 the dropping of the gate may be timed with relation to the movement of the car away from the floor landing.

The operation of my device is as follows: As the elevator approaches the floor landing 48 from either direction, the gate 42 60 is at the floor, closing the entrance to the

elevator, and just before the elevator reaches the landing, the cam 36 comes into engagement with the latch arm 20 throwing it forward into the position shown in Fig. 3 at approximately the time that the elevator reaches the floor. The gate is then raised by hand, a counter-balancing device generally being provided to facilitate the raising of the gate. As the gate is pushed upwardly it engages the latch 30, pushing it inwardly toward the latch arm 20 into the position shown in Fig. 4, provided the housing is so mounted on its fixed support that the latch engages the bottom of the gate directly when in an operative position. If 80 the latch is arranged as shown in Fig. 1, not in engagement with the gate, then no effect is noticed until the angle iron 44 strikes the latch and pushes it inwardly as shown in Fig. 4. After the gate has passed 85 upwardly beyond the latch the force of gravity causes the latch to be thrown outwardly and forwardly into the position shown in Fig. 3, and the gate is then allowed to drop a slight distance and rest 90 upon the latch. So long as the elevator remains at the floor landing, the cam holds the latch arm and latch in operative position as shown in Fig. 3, and the gate remains locked.

When the elevator starts to leave the floor landing the cam moves either upwardly or downwardly and finally out of engagement with the latch arm 20. At this point the latch arm swings rearwardly into the position shown in Fig. 5, the weight of the gate on the latch causing it to swing rearwardly until the lug 22 is in engagement with the stop 26. At this point the latch passes from underneath the gate allowing it to fall by 105 force of gravity. The counter-balancing device is generally arranged for these gates so that the weight of the gate is not exactly counter-balanced but is slightly greater than the counter-balancing weight and thereby 110 the force of gravity causes the gate to fall slowly when the latch is released.

It will be observed that my latch is extremely simple both in construction and operation and can be made at a low cost and 115 after being installed requires absolutely no further care or attention. It is entirely automatic in its operation and always positive. Because of its simplicity it can be applied to various forms of construction of 120 gates and elevators by merely providing a suitable angle iron or other part fastened to the gate, adapted to engage the latch, and by mounting the cam on the elevator in the necessary position.

It is to be understood that my invention may be embodied in various other forms of construction than that shown in the drawings and described hereinbefore and it is not to be limited to the general form shown.

What I claim is:—

1. An elevator gate latch comprising a housing adapted to be secured to a fixed support adjacent to the position of the gate when raised, a latch-arm pivotally hung at its upper end off center in said housing, a latch pivotally mounted on the lower end of said arm and normally held in an outward and locking position by the force of gravity, said latch being movable around its pivot toward the said latch-arm in order to permit the gate to pass upwardly by the latch to its raised position and a cam carried by the elevator car for engaging said latch arm for throwing it forward into locking position when the elevator is at the floor landing.

2. An elevator gate latch comprising a housing adapted to be secured to a fixed support adjacent to the position of the gate when raised, a latch-arm pivotally hung at its upper end off center in said housing, the upper end of said latch-arm being provided with lugs adapted to engage a stop formed on said housing in order to limit the movement of said latch-arm in both directions,

said stop, a latch carried by said latch-arm for supporting the gate in a raised position when said latch-arm is thrown forward into operative position and a cam carried by the elevator car for throwing said latch-arm 30 into operative position when said cam is at the floor landing.

3. An elevator gate latch comprising a housing open at the sides and adapted to be secured to a fixed support adjacent to the 35 raised position of the gate, a latch-arm pivotally hung at its upper end within said housing and normally inoperative, a latch pivotally mounted on the lower end of said latch-arm, said latch being normally held in 40 a forward position by gravity and being provided with a stop to limit its forward movement and a cam carried by the elevator car for throwing said latch-arm into a forward operative position where said latch 45 will lock said gate so long as said car remains at the floor landing.

In witness whereof, I hereunto set my hand this twenty-fourth day of July, 1919.

WILLIAM S. SMITH.
